UNITED STATES PATENT OFFICE.

ALBERT HENRY MIDGLEY, OF ACTON VALE, ENGLAND, ASSIGNOR TO C. A. VANDERVELL & COMPANY, LIMITED, OF ACTON VALE, MIDDLESEX, ENGLAND.

STARTING-MAGNETO FOR INTERNAL-COMBUSTION ENGINES.

1,356,778.

Specification of Letters Patent. Patented Oct. 26, 1920.

Application filed January 29, 1918. Serial No. 214,328.

To all whom it may concern:

Be it known that I, ALBERT HENRY MIDGLEY, a subject of the King of Great Britain and Ireland, and residing at Warple Way, 5 Acton Vale, in the county of Middlesex, England, have invented certain new and useful Improvements in and Relating to Starting-Magneton for Internal-Combustion Engines, of which the following is a 10 specification.

This invention relates to an improved electric starter for internal combustion engines of the kind in which the magneto is employed as the starter.

15 The object of the invention is to provide a starter of the kind above referred to which shall be especially useful for aeroplane engines of the V type, in connection with which it is of great importance to reduce the 20 weight as much as possible.

It is known in starters of the kind referred to, to drive the armature by hand through the intermediary of a suitable gear, and hitherto the contact breaker has been 25 arranged at the end of the armature opposite to that where the driving gear is arranged.

It is also known in connection with magneton to arrange the distributer at one end 30 and the circuit breaker and one member of the gear by which the magneto is operatively connected with the engine at the other end thereof. In such known arrangement, however, the circuit breaker is mounted 35 between the armature and the gear, which does not permit of a standard circuit breaker being used.

The starting magneto constructed according 40 to the present invention, has the distributer mounted at the one end of the armature shaft and the circuit breaker at the other end thereof, while the starting driving gear is arranged between the circuit breaker and the armature for the purpose 45 of being able to use a standard contact breaker and reduce the bulk of the machine.

The accompanying drawing illustrates, by way of example, a sectional elevation of one form of construction according to the invention: *a* is the armature of the magneto 50 which is provided with a primary and secondary winding *b* and *c* respectively; *d* is the circuit breaker which is arranged at the end *A* of the machine; *e* is a distributer arranged at the end *B* of the machine and 55 provided with a segment *f* which is connected to the high tension terminal *g* and is adapted alternately to make contact with two brushes *h* and *i* connected to the distributers of the engine; *j* and *k* are the 60 two members of a driving gear which is arranged at the end *A* of the machine between the armature *a* and the circuit breaker *d*; *l* is a handle by means of which the driving gear is operated for starting 65 purposes. *m* is a condenser.

The handle *l* may be replaced by other means for operating the driving gear, for instance, a spring put under tension, and the driving gear *j* *k* may be replaced by any 70 other suitable gear.

Having now described my invention, what I claim as new and desire to secure by Letters Patent is:—

A starting magneto for internal combustion engines, comprising an armature, an armature shaft, a circuit breaker arranged at one end of the armature shaft, a distributer mounted on the opposite end of the armature shaft and a gear arranged between the armature and circuit breaker for driving the armature shaft together with the circuit breaker and the distributer during the time it is desired to produce the initial sparking for starting purposes, as set 75 forth.

In testimony whereof I have signed my name to this specification.

ALBERT HENRY MIDGLEY.
